Ralph E. Baker
ATTO

ATTORNEY.

prises, in general, a compressor and motor hermetically sealed in a casing 54 and a condenser 56. The cooling of the condensing unit may be accomplished either by forced or natural convection, the latter way being the one shown. Air from the room circulates through the opening 44 and thence over the condenser. A flue (not shown) is preferably provided at the back of the cabinet for enhancing the natural convection effect.

In operation, the compressor withdraws gaseous refrigerant from the evaporator 46 through the vapor conduit 50, compresses the gaseous refrigerant and delivers it to the condenser 56 wherein it is liquefied and from which it is delivered in liquid form to the evaporator 46 through the supply conduit 49. The flow of liquid refrigerant to the evaporator is controlled, preferably, by the supply conduit itself, which comprises a capillary tube of proper dimensions to meter the quantity of liquid refrigerant flowing from the condensing element to the evaporating element during entire operation of the system. This capillary conduit is preferably secured to the return vapor conduit 50 in intimate heat exchange relation therewith. Preferably, the system is intermittently operated, and any suitable conventional method of accomplishing this may be adopted.

Numeral 60 designates, in general, a closed refrigerant circulating system which is adapted to maintain the freezing chamber 38 at temperatures sufficiently low to freeze ice cubes and the like. This system comprises, preferably a coiled conduit 62 which is wrapped around the chamber 38 and in contact therewith from the front to back thereof, the last coil at the rear of the chamber being connected to the first coil at the front by means of a conduit 63. The entire system is secured to the outside of chamber 38 in any suitable heat exchanging relation as by solder or cementing material such as "Hydrolene." Of course, other arrangements of the conduit 62 may be used, or instead of a coiled conduit, plate-like chambers at top and bottom of the freezing chamber connected by conduits may be employed, if desired. The top surfaces of the conduit 62 running across the top of chamber 38 are in thermal contact with the primary cooling element 46, which is adapted to rest thereon or be secured thereto by any suitable clamp (not shown) which permits ready separation of the two elements. Any suitable volatile refrigerant may be used to charge the secondary system 60. The upper surfaces of the conduit 62 in contact with the primary cooling element 46 serve as means for condensing the refrigerant evaporated in the conduit 62 as it circulates through the system. The entire freezing chamber 38 can thus be maintained at a uniform freezing temperature by this closed refrigerant circulating system. The temperature actually obtained can be regulated by the extent of the surface of the system 60 contacting the primary refrigerant evaporator 46 as is well understood in the art. For quick freezing purposes, receptacles such as that indicated by the numeral 65 may be placed on the floor of the freezing chamber immediately above the lowermost portions of the conduit 62 where the liquid refrigerant tends to collect. Any moisture condensing on the outside of the chamber 38 is collected in a sheet metal trough 66 at the bottom of compartment 23 from which it may be drained through a tube 67 into the food compartment 22 where it may be conveniently

collected for ready removal, as will be described later.

Since the freezing compartment 23 is in open communication with the cabinet insulation the low temperature coils therein will freeze out any moisture in the air which contacts the insulation thereby keeping it dry.

Numeral 70 designates, in general, a secondary refrigerating system which is adapted to maintain the food compartment 22 at a relatively high and uniform refrigerating temperature and at a relatively high humidity so that little dehydration of the foods stored therein is accomplished while still keeping the foods at the proper refrigerating temperature. This system includes a cooling or evaporating element designated, in general, by the number 72 and a condensing element designated, in general, by the number 74. These are operatively connected by a liquid supply conduit 76 and a vapor return conduit 77.

The evaporating element 72 comprises, preferably, a sinuous conduit which is secured in any suitable fashion as by soldering or by some cementing material, such as "Hydrolene," in intimate heat conducting relationship to the outside of the inner lining member 35 of the food compartment. This conduit runs back and forth across the bottom of the liner, then progressively upward embracing three sides of the liner until it reaches the top of the lining member where it joins with the vapor return conduit 77.

The condensing element 74 is preferably of similar construction to that of the evaporating element 46 having a plate 80 to which is welded another plate having raised portions thereon for providing a refrigerant passage 82 between the plates. One end of the passage is connected to the liquid supply conduit 76 and the other end to the vapor return conduit 77. The condensing element is disposed in the lower part of the freezing compartment 23 and arranged so that the plate 80 is in direct contact with the lower portions of the closed refrigerant circulating system 60 for condensing refrigerant evaporated in the secondary system. Any desired temperature differential may be maintained between the primary and secondary systems by varying the effectiveness of the transfer of heat from the secondary condenser to the primary evaporator as is well understood in the art. Accordingly in the present arrangement the extent of contact between the secondary condenser and the system 60 may be varied or the refrigerants employed in the respective systems may be changed. In any case, the temperature maintained within the food compartment by the secondary system is sufficiently low to properly refrigerate the foods contained in the compartment and sufficiently high to avoid formation of frost in the food compartment or undue condensation of moisture from the air, thereby preventing the dehydration of the foods.

In operation, the refrigerant evaporated within the secondary system by the absorption of heat from the food compartment is conveyed by the vapor return conduit 77 to the condensing element 74 where it is liquefied and from which it is delivered by gravity through conduit 76 to the section of evaporator 72 at the bottom of the food compartment. It then circulates upwardly through the sinuous conduit wrapped around the walls of the lining member. In this manner the entire food compartment is cooled to a substantially uniform refrigerating temperature while still maintaining said temperature above

the dew point of the air therein under most conditions of operation. Any moisture which does condense is drained through a pipe 84 to a receptacle 86 disposed at the rear of the bin 41.

The entire primary refrigerating system may be removed from the cabinet as a unitary structure. The structure includes the condensing element 41, the evaporating element 46, and an insulated removable closure member 90 which is adapted to close an opening extending across the rear wall of the freezing compartment 23. To remove the structure it is necessary only to move it rearwards from the cabinet. The evaporating element which rests on the freezing chamber is slipped through the opening at the rear of the compartment while the condensing element is slipped out the back of the machine compartment. Thus the entire structure may be removed for repairs and the like.

The freezing chamber with its encircling refrigerating system may also be removed from the cabinet. Any bolts or screws used to secure the chamber in position within the freezing compartment are removed and the entire assembly slipped out the opening at the rear of said compartment without disturbing the secondary system 60. If desired however the sleeve 38, primary evaporator 23 and coiled secondary system may be removed as a unit through the opening in the rear of cabinet closed by plug 90. In this case these parts may be permanently secured together to provide good heat transfer. In this case the opening at the rear of cabinet is made slightly larger to permit the ready removal of these parts as a unit, such unit being shown in Fig. 4.

Although only a preferred form of the invention has been illustrated, and that form described in detail, it will be apparent to those skilled in the art that various modifications may be made therein without departing from the spirit of the invention or from the scope of the appended claims.

I claim:

1. Refrigerating apparatus, comprising, in combination, an insulated cabinet, a low temperature primary refrigerant evaporator disposed within said cabinet, a closed refrigerant circulating system arranged within said cabinet to enclose a freezing zone and having a portion thereof in thermal contact with said primary evaporator, a secondary refrigerant evaporator arranged within said cabinet to substantially enclose a food storage and refrigerating space and a secondary condenser connected to said secondary evaporator and thermally associated with a portion of said closed refrigerant circulating system.

2. Refrigerating apparatus, comprising, in combination, an insulated cabinet, a primary refrigerating system having a low temperature heat absorbing element disposed in said cabinet, a closed refrigerant circulating system disposed within said cabinet and enclosing a freezing zone, said system having a portion thereof associated in heat exchange relation with said primary heat absorbing element, and a secondary refrigerating system disposed within said cabinet and having a cooling element which substantially encloses a food storage zone and a condensing element which is placed in heat exchange relation with a portion of said refrigerant circulating system.

3. Refrigerating apparatus, comprising, in combination, an insulated cabinet having two

compartments, a primary refrigerating system having a cooling element disposed in one of said compartments, a secondary refrigerating system having a cooling element disposed in heat conductive relation with the second compartment and a condensing element disposed in said first compartment, and a closed refrigerant circulating system disposed in said first compartment and enclosing a freezing zone, said system having portions thereof in thermal contact with said primary cooling element and said secondary condensing element respectively.

4. Refrigerating apparatus, comprising, in combination, an insulated cabinet having two thermally insulated compartments, a flat plate primary refrigerant cooling element horizontally disposed across the top of one of said compartments, a flat plate secondary refrigerant condensing element horizontally disposed across the bottom of same compartment, a freezing chamber encircled by a closed sinuous refrigerant conveying conduit and pressed between said flat plate primary cooling element and said flat plate secondary condensing element in direct contact therewith, and a secondary refrigerant cooling element operatively connected to said secondary condensing element and disposed in heat exchange relation with said other thermally insulated compartment.

5. Refrigerating apparatus, comprising, in combination, an insulated cabinet having two compartments, a primary refrigerating system having a cooling element disposed in one of said compartments, a secondary refrigerating system having a cooling element disposed in heat conducting relation with the second compartment and a condensing element disposed in said first compartment, and a freezing chamber having attached thereto in heat conducting relation a closed refrigerant circulating system, said freezing chamber with its refrigerant circulating system being disposed in heat exchange relation with both said primary cooling element and said secondary condensing element.

6. Refrigerating apparatus, comprising, in combination, an insulated cabinet having two compartments, a primary refrigerant cooling element horizontally disposed across the top of one of said compartments, a secondary refrigerant condensing element horizontally disposed across the bottom of same compartment, a freezing chamber having secured in direct contact therewith a closed refrigerant circulating system, said chamber with said circulating system being disposed between said primary cooling element and said secondary condensing element in direct contact therewith, and a secondary refrigerant cooling element operatively connected to said secondary condensing element and disposed in heat exchange relation with said other thermally insulated compartment.

7. Refrigerating apparatus, comprising, in combination, an insulated cabinet having two compartments, a removable primary refrigerant cooling element horizontally disposed across the top of one of said compartments, a fixed secondary refrigerant condensing element horizontally disposed across the bottom of said one compartment, a freezing chamber having secured in thermal contact thereto a closed refrigerant circulating system, said chamber with said refrigerant circulating system being removably disposed between said primary cooling element and said secondary condensing element in thermal contact therewith, and a fixed second-

ary refrigerant cooling element operatively connected to said secondary condensing element and disposed in heat exchange relation with said other thermally insulated compartment.

8. Refrigerating apparatus, comprising, in combination, an insulated cabinet having two thermally insulated compartments, a freezing chamber removably disposed within one of the thermally insulated compartments, a primary refrigerating system including a refrigerant cooling element removably disposed in said one thermally insulated compartment, a secondary refrigerating system disposed in intimate heat exchanging relation with said removable freezing compartment and also disposed in thermal

5 contact with said primary cooling element, said secondary system being removable along with said freezing compartment as a unitary assembly, and another secondary system including a cooling element disposed in heat exchange relation with the other thermally insulated compartment and a condensing element disposed in thermal contact with said first mentioned secondary system, said latter secondary system being permanently fixed in said cabinet, and said primary system being bodily removable as a unit from the cabinet without disturbing either of the two secondary systems.
